UNITED STATES PATENT OFFICE.

REDDIN W. PARRAMORE, OF NEW YORK, N. Y.

DESIGN FOR A HOSE-SUPPORTER.

SPECIFICATION forming part of Design No. 31,816, dated November 7, 1899.

Application filed September 21, 1899. Serial No. 731,230. Term of patent 14 years.

To all whom it may concern:

Be it known that I, REDDIN W. PARRAMORE, a citizen of the United States, residing at New York, in the county of New York and State of New York, have invented and produced a new and original Design for a Hose-Supporter, of which the following is a specification.

This invention relates to a new and original design for a hose-supporter, and has for its object to provide a design of this character that shall be both useful and ornamental.

The leading feature of the design resides in a body of an approximately trapezoidal form, having above the plane of its lower edge a pair of oppositely-located upwardly-divergent side wings and an arched crown-piece offset from the upper edge of the body within the plane thereof and between the planes of the said side wings.

The minor features of the design are the body having the side and top edges thereof curved and a straight bottom edge provided with a continuous series of rounded scallops.

Additional minor features of the design are the upwardly-divergent side wings of the body having straight scalloped edges connecting the curved side and top edges of the body and the offset arched crown-piece having at the top edge thereof an elongated loop projection.

In the drawing the figure is a plan view of a hose-supporter embodying the design contemplated in the present invention.

Referring particularly to the drawing, the numeral 1 designates the main body of the article. This body is approximately trapezoidal in form and is provided above the plane

of its lower edge with a pair of oppositely-located upwardly-divergent side wings 2. The side wings 2 are bounded at the side edges 4 thereof by the inwardly-curved top edge 4 and the similarly-curved side edges 7 of the body 1, and at their ends the said side wings 2 are provided with straight scalloped edges 8, connecting the curved edges 4 and 7 of the body. The approximately trapezoidal body 1 is provided with a straight bottom edge 6, having a continuous series of rounded scallops, and at the top the body 1 is provided with an offstanding arched crown-piece 3. This crown-piece is of an approximately semi-elliptical form and is offset from the upper edge of the body within the plane thereof and between the planes of the side wings 2. The said arched crown-piece 3 joins the top edge 5 of the body on the curved line 5 and is provided with a marginal edge 9 and at the top thereof with an offstanding loop projection 10.

To complete the design the body is provided with parallel stitch-lines 11, following the marginal contour thereof.

Having thus described the invention, what is claimed as new, and desired to be secured by Letters Patent, is—

The design for a hose-supporter herein shown and described.

In testimony that I claim the foregoing as my own I have hereto affixed my signature in the presence of two witnesses.

REDDIN W. PARRAMORE.
